Primary Examiner — Richard Kearney(74) *Attorney, Agent, or Firm* — Rothwell, Figg, Ernst & Manbeck, P.C.(57) **CLAIM**

The ornamental design for a clasp, as shown and described.

DESCRIPTION

FIG. 1 is a front perspective view of a clasp in open position showing my new design;

FIG. 2 is a front perspective view in closed position thereof;

FIG. 3 is a top view in open position thereof;

FIG. 4 is a bottom view in closed position thereof;

FIG. 5 is a left side view in open position thereof;

FIG. 6 is a right side view in closed position thereof;

FIG. 7 is a front view in open position thereof;

FIG. 8 is a rear view in closed position thereof; and,

FIG. 9 is a purse with clasp in closed position thereof.

The purse portion of FIG. 9 shown in broken lines forms no part of the claimed design.
